BUCKLE

Max Hoffman, Roxbury, Mass.

Application March 5, 1947, Serial No. 732,467

2 Claims. (Cl. 24—73)

1

This invention pertains to buckles such as are commonly employed for adjusting the effective length of a strap, for instance a strap forming a part of or associated with a garment. More especially it relates to a buckle having a loop designed detachably to engage a button or equivalent fastener, and having penetrating prongs operative positively to hold a strap adjusted to the desired effective length. Such a buckle is useful, for example, for releasably attaching the forward end of a shoulder strap of a bib-overall to the upper part of the bib.

The shoulder straps employed in work garments are frequently of substantial width—for instance a width of one and one-quarter inches or more is not uncommon. The textile material used in making such garments is customarily close-woven, thick and rather stiff and the buckle must be of sufficient dimensions to accommodate the strap and strong enough to carry the load. When made of the size and of a material heavy enough for practical use, and particularly when the strap has been threaded through the buckle and secured thereto, the buckle and adjacent parts make a substantial area which is almost rigid and which tends to cause discomfort to the wearer and in some cases to interfere with his freedom of movement.

One object of the invention is to provide a buckle which is very flexible, as compared with usual prior buckles of the same general type and which thus conduces to the comfort of the wearer. A further object is to provide a buckle which, although flexible, has sufficient strength, and which is readily manipulable by the wearer of the garment in attaching it to and detaching it from the garment button. A further object is to provide a buckle having penetrating prongs for positive engagement with the garment strap and which also has a button-engaging loop or equivalent element which is movable relatively to the body of the buckle so as thereby to facilitate its engagement with or detachment from a button. A further object is to provide a buckle having the above characteristics, which is simple in construction and easy to make and of relatively low cost. Other and further objects and advantages of the invention will be pointed out in the following more detailed description wherein

Fig. 1 is a plan view of a buckle embodying the present invention;

Fig. 2 is an edge elevation of the buckle of Fig. 1; and

Fig. 3 is a fragmentary front elevation of a garment provided with a shoulder strap and an

2

attaching button, and showing the buckle of the present invention applied thereto.

Referring to the drawings, the improved buckle of the present invention is illustrated as comprising the yoke member 1 which is preferably made by bending a length of wire and flattening it by pressure, although it may be made by stamping from sheet metal or equivalent procedure. However, the yoke may be of other material, for instance, moulded plastic. This yoke is substantially rigid and comprises the straight cross bar 2 which constitutes a stop for the penetrating prongs and which integrally merges with spaced limbs 3 and 4 which, together with the cross bar, define a transversely elongate strap-receiving slot 5. Preferably the cross bar is provided with shallow recesses 6 and 7 for the reception of the pointed ends of the strap-penetrating prongs, although these recesses are not essential, and the forward surface at least of the yoke may be finished in any desired way, for instance by tiny ribs, knurling, or the like to provide an ornamental or pleasing appearance.

The free ends of the limbs 3 and 4 of the yoke are shaped to constitute bearing portions 8 and 9 which may be formed, for example by bending the material of the yoke. If the yoke be formed of other material than metal, for example a moulded plastic, the bearings 8 and 9 will be formed in a way appropriate to such material.

The buckle comprises two independent lengths of wire of appropriate stiffness and size for the intended use, each length of wire comprising the prong portions 10 and 11 respectively, which terminate in pointed ends which, when the buckle is in use, are disposed within the recesses 6 and 7 of the cross bar, each length of wire also comprising a pintle portion 12 and 13 respectively, substantially perpendicular to the corresponding prong and which turns freely in one of the respective bearings 8 and 9. As illustrated, the pintle portions 12 and 13 are substantially longer than the bearings 8 and 9 so that these pintle portions are free to move axially in the bearings as well as to turn in the bearings. Each length of wire also comprises a U-shaped bend 14 and 15 respectively, joining the pintle portions 12 and 13 to substantially horizontal, aligned portions 16 and 17 respectively, the pintle portions, the U-shaped bends and these horizontal portions 16 and 17 collectively defining a transversely elongate strap-retaining slot 18.

Each length of wire is bent at the points 19 and 20 respectively and from these points continues downwardly to form one of the elongate legs 21

and 22 respectively, these legs being spaced from each other and having their lower ends bent to provide the eyes 25 and 26 respectively, each of which has a substantially straight lower side 23 and 24 respectively, these straight sides being normally in alignment. The buckle also comprises a substantially U-shaped button-receiving loop 27, which may be of wire of the same size and material as that which forms the prongs, the free ends of the arms 28 and 29 of this loop being bent to form hooks 30 (Fig. 2) which loosely receive the straight sides 23 and 24 of the respective eyes 25 and 26. The button-receiving loop 27 is free to swing about the axis defined by the parts 23 and 24, this axis being normally parallel to the axis defined by the bearings 8 and 9 of the yoke. The hook members 30 are also free to move axially to a small distance along the straight sides 23 and 24 of the eyes.

In using this improved buckle it is applied, as illustrated in Fig. 3. The lower end portion of the shoulder strap S of the garment G is passed through the strap-receiving slot 5 of the buckle from back to front and after being adjusted to the desired length the prongs 10 and 11 are caused to penetrate the strap so as positively to retain it at its adjusted length. The free end portion of the strap is then preferably passed through the strap-retaining slot 18 from front to rear, its tip usually being concealed behind the bib of the garment.

The garment here illustrated, by way of example, but without limitation, is a bib-overall provided with buttons B near the upper edge of the bib for engagement with the shoulder straps. In accordance with the present invention the button-receiving loop 27 of the buckle is engaged with the button B, thus releasably anchoring the shoulder strap to the bib of the garment.

Since the lengths of wire which form the two prongs 10 and 11 are independent of each other, and may be moved independently axially of the bearings 8 and 9, and since the lower ends of the legs 21 and 22 are loosely connected to the button-receiving loop 27, the prong members, with their legs 21 and 22, are free for substantial, independent movement both toward and away from each other, and in swinging about the axis defined by the bearings 8 and 9. Moreover, as the button-receiving loop 27 is pivotally connected to the prong members, the button-receiving loop may swing relatively to the yoke in a front-to-rear direction. This freedom of the various parts to move relatively to each other provides great flexibility and avoids the stiffness and rigidity which is characteristic of most prior buckles employed for this or similar purposes. With this arrangement it is readily possible to adjust the length of the strap S to the desired length and with the assurance that it will remain at this adjusted length as long as may be desired. On the other hand it is very easy to disengage the strap from the bib of the garment so that the garment may readily be doffed without changing the adjustment of the shoulder strap and as readily donned and secured in position without readjustment.

While one desirable embodiment of the invention has herein been illustrated by way of example, it is to be understood that the invention is broadly inclusive of any and all modifications falling within the scope of the appended claims.

5 I claim:

1. A buckle comprising a yoke having a rigid cross bar and spaced limbs arranged to define a strap-receiving slot, each limb having a bearing at its free end, the bearings being axially aligned, a pair of strap-penetrating prongs each having a sharp end designed to contact the cross bar of the yoke, each prong having a pintle portion arranged to turn and to slide axially in one 10 of the yoke bearings respectively, the prongs with their pintle portions being independent of each other, each pintle portion integrally joining an elongate leg member, each leg member having an eye at its free end, each eye having a substantially straight side, the straight sides of the two 15 eyes being in alignment, and a button-engaging loop comprising spaced arms whose free ends are hooked over the straight sides of the respective eye and movable longitudinally of said straight sides.

2. A buckle comprising a yoke having a rigid cross bar and spaced limbs arranged to define a strap-receiving slot, each limb having a bearing at its free end, the bearings being axially aligned, 20 two independent lengths of wire each having a portion which constitutes a strap-penetrating prong sharp at its free end and engageable with the cross bar of the yoke, each length of wire also comprising a pintle portion perpendicular to the 25 prong and turning and being axially movable in one of the respective bearings of the yoke, each length of wire also comprising a U-shaped bend, said bends being opposed and collectively constituting a strap-retaining slot, each length of 30 wire also comprising an elongate leg portion terminating in an eye having a substantially straight side, said straight sides being aligned, and a U-shaped button-receiving loop having 35 hooks at the ends of its legs which are slidable 40 along the straight sides of the respective eyes.
